UNITED STATES PATENT OFFICE.

CHARLES M. WRIGHT, OF ANDERSON, INDIANA, ASSIGNOR OF ONE-THIRD TO ALFRED L. REED AND ONE-THIRD TO THOMAS S. GETTLE, OF ANDERSON, INDIANA.

CHEESE-CUTTER.

No. 910,443.

Specification of Letters Patent.

Patented Jan. 19, 1909.

Application filed January 17, 1907. Serial No. 352,760.

To all whom it may concern:

Be it known that I, CHARLES M. WRIGHT, a citizen of the United States, residing at Anderson, in the county of Madison and State of Indiana, have invented certain new and useful Improvements in Cheese-Cutters, of which the following is a specification, reference being had therein to the accompanying drawing.

My invention relates to improved mechanism for controlling the actuating mechanism of the revoluble table of cheese-cutters to impart a regular movement to said tables, and it consists in the mechanism hereinafter described and particularly pointed out in the claims.

The object of this invention is to provide a simple and accurate means whereby the motion of the actuating lever may be adjusted and the amount of rotation or movement of the cheese-carrying-table of the apparatus may be controlled to move equal and unvarying fractions or portions of a revolution corresponding to any particular setting or adjustment of the means whereby the actuating-lever is controlled to divide a cheese into equal portions, and to provide a means whereby the momentum of the cheese-carrying-table may be arrested instantaneously at the termination of each fractional rotation of said table. I attain these objects by means of the mechanism illustrated in the accompanying drawings in which like reference numerals designate like parts throughout the several views.

Figure 1. is a perspective view of a cheese cutter embodying my invention; Fig. 2. is a detail broken perspective view of a portion of the base of the apparatus showing the setting lever thereof; Fig. 3. is a plan view of the apparatus showing the cheese-carrying-table and the cheese-cutting knife removed in order to exhibit the actuating mechanism of said cheese-carrying-table; Fig. 4. is a sectional view of the same taken along the line A. B. in Fig. 3.; Fig. 5. is a view similar to that of Fig. 3. showing the cheese-carrying-table and its supporting-frame removed to exhibit the mechanism of the actuating lever and the manner of setting the controlling mechanism thereof whereby a cheese may be cut into portions of a desired weight and value; Fig. 6. is an enlarged detail view of the actuating-lever of the apparatus showing the friction-clutch

arms or grips thereof; Fig. 7. is an enlarged detail longitudinal sectional view of the ball-bearing-nut of the setting-screw and its socket, and taken along the line C. D. in Fig. 5.; Fig. 8. is a detail side view of the locking-bar of the actuating-lever whereby the momentum of the revolving cheese-carrying-table is arrested, and looking in the direction of the arrow *a* in Fig. 3. Fig. 9. is a similar view of said locking-bar looking in the direction of the arrow *b* in Fig. 3. and; Fig. 10. is a detail perspective view of the setting-lever.

The base-frame is composed of the ring 1, the radially extending arms 2 and 3, and the supporting feet 4. A boss 5 is formed integral with the arms 2 and 3 and is situated centrally of the ring 1 and said boss is provided with a central bore into which the depending center-pin 6 of the table-frame is fitted to revolve. The table-supporting-frame is composed of the rim 7, the arms 8, and the center boss 9, all of which are preferably formed in one integral piece. Another boss 10 is situated between the upper boss 9 and the depending-center-pin 6, all of which bosses and center-pin are on the same axis or center, and said intermediate boss 10 is turned on its outer peripheral surface to form a smooth bearing for the actuating lever 11 which latter carries the friction clutch-arms for operating the cheese-carrying-table.

The boss 10 is slightly larger than the center-pin 6 to form a bearing-shoulder which rests upon the top-surface of the boss 5 to assist in supporting the cheese-carrying-table, its frame, and the cheese placed upon said table. This shoulder also prevents a binding of the actuating lever 11 between the table-frame-boss 5 and the boss 9 of the table-supporting-frame base. The depending-flange or lower rim 12 of the table-frame is turned truly on its inner and outer peripheral surfaces and to a uniform thickness so that it will be the more readily engaged or gripped by the clutch-arms of the actuating lever 11 and also for the purpose of making said rim 12 concentric with the axis of the center-pin 6. The bottom edge of the depending-flange or rim 12 is turned truly to rest and to rub upon its supporting-blocks 13 which are formed integral on the arms 2 of the frame-base, which blocks are provided not only for the purpose of sup-

porting and steadyng the cheese-table and its supporting-frame, but also to operate as a brake for preventing the too free movement of the cheese-carrying-frame and its 5 table.

The pressure of the rim 12 upon the supporting-blocks 13 varies directly in proportion to the load placed upon the cheese-carrying-table and consequently the brake 10 power of said blocks 13 varies in the same proportion, that is to say, when the load on the revoluble cheese-carrying-table is light the bearing pressure of the rim 12 upon the supporting-blocks 13 is light and the braking 15 force is light in the same proportion, and when the load on the said table is increased the bearing pressure of said rim 12 upon said supporting blocks 13 is increased in the same proportion and the braking force 20 is likewise increased in the same proportion. The actuating-lever 11 is provided with a boss 14 which is situated about the center of the length of the lever and said boss is bored to fit on the turned boss 10 previously 25 scribed. Friction clutch-arms 15 are pivotally mounted on the top side of the actuating lever 11 by their pivotal pins 16 which latter are so situated on said lever that the said clutch-arms will each be at a slight 30 angle with a radial line extending from the point of contact of the engaging end of the clutch-arm with the inner surface of the rim 12, so that the engaging or gripping ends of 35 said clutch-arms 15 may the more readily engage the turned inner surface or periphery of the depending flange or rim 12 to rotate the table-frame a desired portion of a revolution in one direction only, that is, from left to right, with each oscillation of 40 said actuating-lever 11.

Clutch-arm retaining-springs 17 are secured on the top side of the actuating-lever 11 in position thereon to press freely against said clutch-arms 15 to maintain their engaging 45 ends in constant contact with the depending-flange or rim 12.

A clutch or retaining-cam 18, for retaining said depending flange or rim 12 and preventing a backward movement of the cheese-carrying-table while the actuating-lever 11 is being reversed or moved from right to left, as will be hereinafter described, is pivotally mounted on the top side of one of the brake blocks 13 in such a position thereon 50 as to contact with the outer peripheral surface of the depending flange or rim 12. Opposite said cam 18 and on the inner side of the depending flange or rim 12 is situated on one of the arms 2 of the base frame, a clutch arm 18^a which is pivoted on a pin 19 55 in such position that its gripping or contacting end will engage the inner turned peripheral surface of said depending flange or rim. A tension coil-spring 20 is connect- 60 ed at one end to the spring-arm 21 of the

retaining-cam 18, and at its other end to the spring arm 22 secured to the clutch-arm 18^a, so that both said inside clutch-arm and said outside retaining-cam are brought simultaneously into and maintained in contact with 70 said depending flange or rim 12 to prevent it rotating in a direction from right to left.

The setting-lever 23, whereby the necessary throw or motion of the actuating-lever 11 is controlled to revolve the cheese-carrying-table a certain fractional distance or portion of a revolution, to revolve a cheese under the edge of the cutting-knife by that quantity that is to be cut off the cheese, is pivotally mounted at one end to the arm 3 near the 80 center of the supporting-frame by a pin 24, and said setting-lever 23 is of such a length that its swinging end will extend beyond the front projecting portion 38 of the ring 1 of the base-frame so that its handle or 85 outer end will sweep over the face of the value scale 25. A stop or setting-pin 26 is situated on said setting-lever 23 some distance in advance of the pin 24 and is of a length sufficient to project above the top side 90 of said setting-lever and into the plane of the sweep of the actuating-lever 11.

The setting-lever 23 is adjusted to any of the graduations of the value scale 25 by means of mechanism which I will now proceed to describe. The reach-rod 28 is screw-threaded at one end and on its opposite end is provided a fork 29 which is adapted to receive the setting-lever 23 to be pivotally connected thereto by the connecting-pin 30. 100 The ball-bearing 31 is provided with a neck portion 31^a on the end of which is secured a thumb-grip 27 whereby the said ball-bearing 31 may be readily turned or revolved in its socket bearing. The ball-bearing 31 is 105 turned in the form of a sphere and fitted into and adapted to turn in its socket-bearing 32 formed integral on the ring 1, and said ball-bearing is retained in said socket-bearing 32 by a retaining-cap 33 which latter is screwed 110 into the threaded bore 34 till its concave bearing end contacts with the surface of the ball-bearing in such a way as not to clamp the latter in its socket bearing, but permit it to freely rotate to screw or unscrew the 115 reach-rod 28 to move or swing the setting-lever 23 either to the right or to the left to control the motion of the actuating-lever 11.

The value scale is graduated or divided into divisions which are indicated by numbers representing certain specific values and these numbers ascend or increase in value from left to right, to accord with the setting mechanism whereby the actuating lever is controlled.

The direct value scale 25 is made in the form of an arc of a circle and is situated to encircle a portion of the outer periphery of the ring 1 of the base-frame to which it is permanently secured in position to be 130

within the scope of the sweep of the end portion of the setting-lever 23. The scale 25 is also situated so that its graduated face will be in close proximity to the edge of the 5 swinging end of the setting-lever 23 or the said lever may rub on the graduated face of said scale so that the said setting-lever 23 may be the more accurately adjusted to a certain or required value represented on the 10 face of the scale.

The scale 25 is graduated in ascending values or in graduations the numerical values of which increase from left to right; so that if a cheese weighing two pounds is placed 15 upon the revoluble cheese-carrying-table of the machine, the setting-lever 23 may be set to that graduation designated by that figure representing the value of a two pound cheese and if this size of a cheese were replaced by 20 a cheese weighing five pounds, the setting-lever 23 would be moved and adjusted to that graduation on the scale 25 designated by that figure representing the value of a five pound cheese, in order that a portion of 25 the cheese be cut off that will be equal in value to the portion cut off the smaller cheese.

The actuating lever 11 is provided with a cranked - handle - end - portion 36 and is arranged 30 to extend over and bear upon the supporting-bar 27 which latter is provided with the end supporting-feet 37^a whereby it is supported in position upon the top side of the front projecting portion 38 of the 35 ring 1 of the frame-base, and said bearing or supporting-bar 37 operates as a support for the free cranked end-portion of said actuating lever 11.

A locking-bar 39 by which the play of the 40 actuating-lever 11 is limited in one direction to a constant fixed stopping point and whereby the momentum of the revoluble cheese - carrying - table and its supporting frame is instantaneously arrested, is of an 45 L-form, as shown in Figs. 3, 4, and 5, and in detail in Figs. 8 and 9. One leg of said clutch-bar is provided with a slot 40 through which a cap-screw 41 is passed whereby said locking-bar 39 is pivotally connected to the 50 top side of the ring 1 of the base-frame. By means of the slot 40 the requisite amount of play of the locking-bar 39 is provided to insure the proper working of said locking-bar. The other leg of said locking-bar extends 55 over the top side of that end of the actuating-lever 11 opposite its cranked end, so that the depending stops or fingers 42 extend over the edges of the lever 11 to fix or limit the throw or oscillation of said actuating-lever and on the other slotted leg of 60 said locking-bar are situated to project upwardly from the top side thereof, the gripping fingers 43 between which the depending flange or rim 12 of the table frame is 65 situated, so that, when the actuating lever 11

is swung or oscillated to its extreme end of travel or sweep, whether set for a shorter or a longer stroke, the grip-pins or fingers 43 engage the depending flange or rim 12 at that point of the oscillation and thereby prevent 70 a further rotation of the revoluble cheese-carrying-table and the parts connected thereto, and further, no motion can be imparted to said table to move or rotate it in a backwardly direction till such times as the rim 75 12 of the table frame is released which is accomplished by moving the actuating-lever 11 to cause the fingers 43 to disengage said rim.

A standard 44 is situated on that side of 80 the frame base opposite the value scale 25 and terminates in a hinge fork 45 between the bifurcations of which the hinged end 46 of the knife lever 47 is pivoted by a hinge-pin 48. The cheese cutting-knife 49 is removably secured to said knife-lever 47 by the knife-securing bolts 50, as shown particularly in Fig. 1.

The retaining or tie-bolt 51 passes through the center bore of the boss 10, the pin 6 and 90 the boss 5 of the supporting-frame of the cheese-carrying-table and said retaining or tie-bolt 51 is provided for the purpose of retaining the cheese supporting-table-frame securely in position on its supporting base-frame.

The table 52 is of a disk-form and may be of wood secured centrally upon the table-supporting frame.

To set the setting lever 23 to limit the 100 throw of the actuating-lever 11, that is, to fix the rotation of the cheese-supporting-table 52 to any desired fraction of a rotation or cycle corresponding to a required value or portion of cheese to be cut from a cheese, 105 one proceeds as follows:—The cheese to be divided into portions is first weighed to ascertain its total value. This value having been ascertained, the setting lever 23 is moved till its beveled edge 23^a is set to the 110 graduation designating the total value of the cheese to be divided into portions having a certain fixed value. When multiples of this value are required the actuating-lever 11 is oscillated the required number of times 115 to make the total value of the portions.

The operator moves the actuating-lever 11 first toward the left till the inner contacting edge of the gap 13^a contacts with the stop-pin 26 and arrests the actuating-lever 120 11 to prevent its further motion in that direction. The operator next moves said actuating-lever 11 in the opposite direction its full extent, that is to say, he moves or swings the actuating-lever 11 toward the 125 right to revolve the cheese-carrying-table to move the required portion of the cheese beyond the cutting edge of the cheese-cutting-knife that is required to be severed from said cheese, and this motion of the actuat- 130

ing-lever 11, when moved its full extent or throw, is arrested by the locking-bar 39 which prevents any further motion of said actuating-lever 11 and arrests, at the same time, the motion of the cheese-carrying-table. The cheese-cutting-knife is now brought down with its cutting-edge against the cheese and the required portion of the desired weight is severed from the cheese.

10 I claim:—

1. In a device for cutting cheese into portions of a predetermined value, the combination with a knife, a cheese-carrying-table, and an actuating-lever, of a stop, a setting-lever carrying said stop, a value indicating means, and means whereby said setting-lever is positively operated and adjusted to set said stop.

2. In a device for cutting cheese into portions of predetermined values, the combination with a knife, a cheese-carrying-table, and an actuating-lever, of a stop, a setting-lever carrying said stop, a value indicating scale situated so that its graduated face is adjacent to the swinging end of said setting-lever, a stationary revoluble screw-nut, a reach-rod connected to said screw-nut at one end and to said setting-lever at its other end whereby said setting-lever is accurately and positively adjusted to a predetermined value on said scale.

3. In a device for cutting cheese into portions of predetermined values, the combination with a knife, a cheese-carrying-table, and an actuating-lever, of a stop, a setting-lever carrying said stop, a value scale, a ball-bearing screw-nut, thumb-lugs on said screw-nut, a reach-rod screwed into said ball bearing screw-nut at one of its ends, said rod having its opposite end pivotally connected to said setting-lever whereby the latter is accurately and positively moved and adjusted to a graduation on said scale representing the value of the portion to be severed from the cheese.

4. In a device for cutting cheese into portions of predetermined values, the combination with a knife, a cheese-cutting-table, and an actuating-lever, of a locking-bar pivoted at one end to a fixed pin, engaging fingers depending from the under side of said bar and situated to extend over each edge of the

actuating-lever and engaging fingers projecting upwardly from the top side of said bar and situated so as to simultaneously engage the cheese-carrying-table and the actuating-lever at the end of the oscillation of the latter to stop its movement and the cheese-carrying-table.

5. In a device for cutting cheese into portions of predetermined values, the combination with a knife, a cheese-carrying-table having a depending flange or rim, and an actuating-lever, of a locking-bar formed of two integral legs situated at right angles to each other, one of which is provided with a longitudinally extending pivotal pin opening or slot, a fixed pivot-pin passing through said slot, fingers extending from the top side of said slotted angle leg to engage said flange or rim of said table, and fingers depending from the under side of the other angle leg to embrace the oscillating end of said actuating-lever simultaneously with the engagement of said rim.

6. In a device for cutting cheese into portions of predetermined values, the combination with a knife, a cheese-carrying-table having a depending flange or rim, and an actuating-lever, of a locking-bar formed of two integral legs situated relatively to each other to form a right angle, one leg of which is provided with a longitudinally extending oblong slot, the other situated to extend over an oscillating portion of said actuating-lever, a fixed pivot-pin passing through said slot, fingers extending from the top side of said slotted angle leg to engage said flange or rim and fingers depending from the under side of the other angle leg to embrace the oscillating end of said actuating-lever over which the latter angle leg extends, said fingers of said locking-bar so situated that they operate to simultaneously engage said depending flange or rim, and said actuating-lever when the latter has terminated its stroke.

In testimony whereof I affix my signature in presence of two witnesses.

CHARLES M. WRIGHT.
